LA VERNE NOYES, OF CHICAGO, ILLINOIS, ASSIGNOR TO AERMOTOR COMPANY, OF CHICAGO, ILLINOIS, A CORPORATION OF ILLINOIS.

PAWL-AND-RATCHET MECHANISM.

1,245,371.

Specification of Letters Patent.

Patented Nov. 6, 1917.

Application filed April 17, 1917. Serial No. 162,816.

To all whom it may concern:

Be it known that I, LA VERNE NOYES, citizen of the United States, residing at Chicago, in the county of Cook and State of Illinois, have invented a certain new and useful Improvement in Pawl-and-Ratchet Mechanism, of which the following is a full, clear, concise, and exact description.

My invention relates to ratchet wheels and their controlling mechanism.

As I have preferably practised my invention, the ratchet actuating mechanism is electro-mechanical, embracing an electro-magnet for storing pawl actuating power and for placing the pawl in position to operate upon the ratchet, and a spring in which the actuating power is stored and serving to actuate the pawl upon deënergization of the magnet. In such an arrangement the pawl cannot be positioned by the magnet to turn the ratchet until the magnet has been sufficiently energized fully to attract its armature, so that the pawl cannot function to turn the ratchet upon mere partial energization of the magnet and the consequent mere partial movement of its armature. The pawl mechanism desirably includes a device to prevent the actuated ratchet from creeping in either direction, this device being preferably a toe formation upon the pawl that enters a recess at the base of the engaged ratchet tooth. The pawl also carries or is united with a holding dog also to obstruct creeping of the ratchet and operating to prevent momentum of the pawl and ratchet or other force from carrying the ratchet beyond the position in which the pawl is to push it.

I will explain my invention more fully by reference to the accompanying drawing showing the preferred embodiment thereof and in which Figure 1 is a view illustrating the relative positions of the parts of my device when the magnet is deënergized; Fig. 2 is a view illustrating a relative position of the parts when the magnet is fully energized and its armature structure has been fully attracted; and Fig. 3 is a view on a larger scale illustrating details of construction.

Like parts are indicated by similar characters of reference throughout the different figures.

The ratchet wheel 1 has teeth 2 whose faces 3 are on radii of the wheel and are engaged by the pawl 4 to move the wheel step by step. The pawl is carried upon a

stem 5 that operates through an opening 6 formed in a post 7 that projects from the mounting 8 on which the wheel is mounted to turn. The base 9 of the stem is linked to the overlapping ends of the armatures 10. 60 The stem base 9 carries a stud 11 which is surrounded by one end of a compression spring 12 which bears upon the adjacent end of the stem base. The other end of the spring is anchored to a post at 13 carried 65 by the mounting board or plate 14 that supports the spools 15 of the electro-magnet and their armatures 10.

When the magnet is fully energized its armature structure assumes the position 70 shown in Fig. 2. In assuming this position the armatures compress spring 4 to store pawl actuating power therein. When the magnet is deënergized the spring distends and places the parts in the position shown 75 in Fig. 1. When the armature structure is fully attracted, the pawl 4 rides over the crown of a fresh tooth and drops before the radial face of this tooth and upon the sloping face of the next tooth, results that do 80 not occur unless the magnet is fully energized. When the compression spring expands to give up the pawl actuating power stored therein by the magnet, it presses upon the stem of the pawl and forces the outer 85 end of the pawl against the radial face of the fresh tooth before which the pawl has been positioned, the movement having been sufficient, in the construction as illustrated, 90 to turn the ratchet wheel just one tooth.

The pawl stem also carries or is united with a holding dog 16 that is so fixed with respect to or connected with the pawl as to be presented to the sloping face of another fresh tooth on the opposite side of the wheel 95 from the pawl engaged tooth, the dog being engaged by the opposing tooth of the wheel when the wheel has been pushed one tooth space by the pawl, whereby the wheel cannot be carried by its momentum and the 100 momentum of the pawl beyond the tooth space through which the pawl pushes it, the dog also obstructing movement.

When the pawl is brought to rest, the tooth that the pawl pushed upon remains in 105 engagement with the pawl to prevent the ratchet wheel from creeping backward. The pawl also drops into engagement with the ratchet wheel to prevent said wheel from creeping forward. This latter engage- 110

ment is desirably afforded by means of a toe 16' that is receivable in the recess or notch 17 that is provided at the base of each tooth between its radial face and the sloping face of the next tooth. When the pawl is moved to position to engage a fresh tooth, the toe, which is beveled on its under side, easily rides out of the notch.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. The combination with a ratchet wheel; of a pawl adapted to push upon the teeth of the ratchet wheel to turn said wheel; a spring for operating the pawl; an electromagnet operating, when energized, to store pawl operating power in said spring and to place the pawl in position to push upon a fresh tooth of the wheel; and a holding dog united with the pawl to move therewith and serving to be engaged by the ratchet to obstruct movement of the ratchet, said pawl and wheel having interengaging formations that prevent the wheel from creeping forward.

2. A ratchet wheel, in combination with a pawl for operating the ratchet wheel, said pawl and wheel having interengaging formations that prevent the wheel from creeping forward.

3. A ratchet wheel, in combination with a pawl for operating the ratchet wheel, said pawl having a toe and said ratchet wheel having recesses at the bases of its teeth, one receiving said toe when the pawl has moved the ratchet wheel, to prevent the ratchet wheel from creeping.

4. A ratchet wheel, in combination with a pawl for operating the ratchet wheel, said pawl having a toe and said ratchet wheel

having recesses, one receiving said toe when the pawl has moved the ratchet wheel, to prevent the ratchet wheel from creeping.

5. A ratchet wheel, in combination with a pawl for operating the ratchet wheel, said pawl and wheel having interengaging formations that prevent the wheel from creeping forward; and a holding dog united with the pawl to move therewith and serving to be engaged by a fresh tooth when the pawl finishes its movement of the ratchet to obstruct movements of the ratchet.

6. A ratchet wheel, in combination with a pawl for operating the ratchet wheel, said pawl and wheel having interengaging formations that prevent the wheel from creeping forward; and a holding dog united with the pawl to move therewith and serving to be engaged by the ratchet when the pawl finishes its movement of the ratchet to obstruct movement of the ratchet.

7. A ratchet wheel, in combination with a pawl for operating the ratchet wheel, said pawl having a toe and said ratchet wheel having recesses at the bases of its teeth, one receiving said toe when the pawl has moved the ratchet wheel, to prevent the ratchet wheel from creeping; and a holding dog united with the pawl to move therewith and serving to be engaged by a fresh tooth when the pawl finishes its movement of the ratchet to obstruct movement of the ratchet.

8. A ratchet wheel, in combination with a pawl for operating the ratchet wheel, said pawl having a toe and said ratchet wheel having recesses, one receiving said toe when the pawl has moved the ratchet wheel, to prevent the ratchet wheel from creeping; and a holding dog united with the pawl to move therewith and serving to be engaged by a fresh tooth when the pawl finishes its movement of the ratchet to obstruct movement of the ratchet.

In witness whereof, I hereunto subscribe my name this 10th day of April, A. D., 1917.

LA VERNE NOYES.
